LOOSE-LEAF CONSTRUCTION

Victor Havel, Chicago, Ill., assignor to L. L. Paper Products, Inc., Chicago, Ill., a corporation of Illinois

Application September 7, 1942, Serial No. 457,627

4 Claims. (Cl. 129—1)

This invention relates to a paper loose leaf construction.

Among the objects of my invention is to provide a calendar made entirely out of paper, Bristol board, cardboard, pasteboard or the like into which leaves may be freely inserted, turned and withdrawn and which will hold said leaves firmly and prevent accidental displacement. Another object is to create a calendar having face and leaf holding elements formed from the face itself without additional or extraneous materials. Another object is to supply a calendar economical of manufacture, made of materials procurable during times of scarcity or war, which will function satisfactorily and be lasting in wear and such other objects, advantages and capabilities as will later more fully appear and which are inherently possessed by my invention.

While I have shown in the accompanying drawings preferred embodiments of my invention, yet I wish it understood that the same are susceptible of modification and change without departing from the spirit of my invention.

Referring to the drawings, Fig. 1 is a perspective view of one form of my calendar; Fig. 2 is a top plan view of the leaf 25; Fig. 3 is a top plan view of one form of my sheet; Fig. 4 is a detailed perspective view of the single strap; Fig. 5 is a broken perspective view of my calendar showing in detail the straps with a plurality of scores, and Fig. 6 is a similar view showing in detail looped straps.

One embodiment selected to illustrate my invention comprises a sheet 11 of Bristol board, cardboard, pasteboard or other firm paper material.

A pair of spaced longitudinally extending cuts 18 and 19 form between them a strap 20. In Fig. 1, I have shown a pair of laterally spaced straps 20, and in Fig. 4 I have provided a single strap 50 of greater lateral extent located substantially in the center. I may provide any desired number of straps without departing from the spirit of my invention.

Said sheet 11 has a lateral score 60 extending between each set of cuts 18 and 19 at their upper ends. Said sheet 11 also has a lateral score 61 extending between each set of cuts 18 and 19 at their lower ends.

A slit 62 extends laterally from one of the side edges 63 of sheet 11 to opening 35 below strap 20, continuing laterally between other openings 35 provided and then extending laterally to the opposite side edge 64 of sheet 11.

Above slit 62 and extending inwardly from

edge 63 to cut 18, and from edge 64 to cut 19 and between inner cuts 18 and 19 are upper tongues 65. Below cut 62 and extending inwardly from edge 63 to cut 18 and from edge 64 to cut 19 and between inner cuts 18 and 19 are lower tongues 66.

For use, straps 20 are bent inwardly on scores 60 and 61. Lower tongues 66 are positioned to overlap with upper tongues 65 so that straps 20, bent outwardly on scores 21, extend diagonally upwardly.

In this open position straps 20 (and strap 50) are adapted to receive, permit turning and permit proper unloading of cut sheets of paper 25. The sheets of paper 25 have at their inner edges 26 a cut 27 extending through arms 28 on either side thereof to a slot 29. The cut 27 permits moving of the sheet 25 until the strap 20 is within the slot 29. Accidental removal is prevented for practical purposes by arms 28 engaging straps 20.

Additional longitudinal scores 30 may be provided on straps 20 and 50, spaced longitudinally from score 21 to permit straps 20 and 50 to be bent outwardly thereon for the accommodation of desired thicknesses of paper sheets loaded on said straps. See Fig. 5.

My straps 20 and 50 may be formed without any scores 21 or 30 thereon, curving between scores 60 and 61 to form a loop, as shown in Fig. 6.

The degree of the overlap of tongues 65 and 66 and the positioning of score 21 or scores 30 determines the height and angle of the straps 20 and 50.

When I desire to use my construction for a calendar, I prefer the form shown in Fig. 1, wherein lower tongues 66 overlap upper tongues 65 less than half way, and score 21 on each strap 20 is positioned below the center of strap 20. This construction provides an angle just short of a right angle and particularly adapted to hold the leaves 25 of the calendar.

It is of course within the contemplation of my invention that upper tongues 65 may overlap lower tongues 66 instead of tongues 66 overlapping tongues 65, without departing from the spirit of my invention, and that said tongues may overlap each other to any desired degree.

The tongues may be attached together at their overlapping portions by any suitable means, such as adhesives, pins or the like. While I prefer to attach sheet 11 to a back 67 by adhesives or any other suitable means, yet I may omit the back entirely.

Sheet 11 with its upper portion 68 and its lower portion 69 may be of a size to cover the back 67, or it may be abbreviated in the form of a stub construction to be attached to a larger back 67.

Ordinarily my construction is to be used for calendars and is constructed with the longitudinal axis as predominating. My construction may, however, be turned at right angles on a lateral axis for use as a desk calendar pad.

Having thus described my invention, I claim:

1. A loose leaf calendar construction comprising a sheet of paper, said sheet having laterally spaced pairs of spaced cuts extending longitudinally to form straps, said sheet having a slit extending laterally from each side edge of said sheet to the outer of each of said spaced cuts and between the inner of each of said spaced cuts to form upper and lower tongues on said sheet, said straps having lateral scores at their upper and lower junctures with said sheet, and bent inwardly thereon, said straps also having a score thereacross, and bent outwardly thereon, said lower tongues overlapping said upper tongues for extending said straps diagonally upwardly for the reception, withdrawal and turning thereon of sheets, and a back, said sheet attached to said back.

2. A loose leaf construction comprising a sheet of paper, said sheet having at least one pair of spaced cuts to form a strap and an opening therebeneath, said sheet having a slit extending from opposite edges of said sheet to and between each opening provided to form upper and lower tongues on said sheet, each strap provided having scores at its upper and lower junctures with

said sheet and bent inwardly thereon, each strap having at least one score thereacross and bent outwardly thereon, said upper and lower tongues at least partially overlapped for extending each strap provided diagonally upwardly for the reception, withdrawal and turning thereon of sheets, and a back, said sheet attached to said back.

3. A loose leaf construction comprising a sheet 10 having at least one pair of spaced cuts to form a strap, and an opening therebeneath, said sheet having a slit extending from opposite edges of said sheet to and between each opening provided to form upper and lower tongues on said sheet, 15 each strap provided having scores at its upper and lower junctures with said sheet and bent inwardly thereon, said upper and lower tongues at least partially overlapped for extending each strap provided diagonally upwardly for the reception, withdrawal and turning thereon of sheets, and a back, said sheet attached to said back.

4. A loose leaf construction comprising a sheet 25 having at least one pair of spaced cuts to form a strap, and an opening therebeneath, said sheet having a slit extending from opposite edges of said sheet to and between each opening provided to form upper and lower tongues on said sheet, 30 each strap provided having scores at its upper and lower junctures with said sheet and bent inwardly thereon, said upper and lower tongues attached in at least partially overlapped position for extending each strap provided diagonally upwardly for the reception, withdrawal and turning 35 thereon of sheets.

VICTOR HAVEL.
